COIN COLLECTING AND RECEIPTING DEVICE

Norman E. Moxley, Ellicott City, Md.

Application July 7, 1955, Serial No. 520,423

3 Claims. (Cl. 194—83)

This invention relates to a coin operated receiving device, and more specifically, the invention pertains to a coin collector especially designed to collect small fines such as, for example, traffic fines, and to receipt the ticket given to the violator by an officer.

The present invention is a continuation-in-part of my copending applications Serial No. 410,245, filed February 15, 1954, entitled "Coin Collector for Traffic Violations"; and Serial No. 457,329, filed September 21, 1954, and entitled "Coin Collecting and Receipting Device."

My prior applications as well as the present case relate to mechanisms which are designed to facilitate the collection of minor fines involving traffic violations as, for example, over-time parking, or parking in an unauthorized space. In such an instance, a parking ticket is made out by an officer who designates the nature of the violation and gives the same to the offender. Under the present practice it is necessary for the violator to make a special trip to the police station to pay the fine. Of course, this normally consumes a considerable amount of time for the violator and also involves a large amount of bookkeeping by the police department. It is a well known fact that the very inconvenience involved in making a trip to the police department to make such a payment results in delay or failure to pay, in fact, which in turn leads to a loss of revenue. In the event that the violator delays making payment, the original small fine is normally increased, and should the driver or violator fail to pay the fine he may be forcibly escorted to the police station which gives rise to unfortunate and strained public relationship between the officials of the department and the citizens.

Consequently, one of the primary objects of this invention is to provide a fine collecting device and mechanism for receipting, as paid, the ticket issued by an officer in connection with a minor traffic or other violation.

Another object of this invention is to provide a device of the type to which reference has been made above, such device providing a system for the payment of traffic violations which includes a ticket which is to be filled in by an officer, the ticket being insertable within a coin operable machine which will punch the ticket "Paid," and simultaneously therewith remove a coupon from the ticket for use as a record by the police traffic department, and at the same time leave the punched portion of the ticket as a receipt for the offender, all of these objects being accomplished without the identification of the officer to the violator, while at the same time providing a non-fixable record for the accounting department of the police department.

A further object of this invention is to provide, in a mechanism of the type described, means for rejecting coins of the improper denomination.

A still further object of this invention is to provide means in a coin operated device of the type referred to above effectively preventing the operation of the device until the proper number of coins have been deposited therein.

2

This invention also contemplates the provision of means in a coin operated device of the type described above which not only prevents the operation of the device until the proper number of coins have been deposited therein, but also impales the inserted ticket to prevent the removal thereof until the proper number of coins have been inserted into the device.

As a still further object of this invention, it is proposed to provide a coin collecting device which is so constructed and arranged that it may be operated by inserting a single coin of a given denomination or a plurality of coins of smaller denomination but equal in value to the larger coin.

This invention is also directed to the provision of a special ticket adapted for use in a device constructed in accordance with the present invention, the ticket serving as notice of a fine, the amount thereof, a receipt for the violator, and a severable coupon to be retained in the machine for the bookkeeping department of the police traffic department.

It is still another object of this invention to provide a coin collecting and ticket receipting device so constructed as to be readily placed in a plurality of stores, garages, filling stations, and other similar sites scattered throughout a local area.

This invention contemplates as a still further object thereof the provision of a device of the type described which is inexpensive to manufacture, non-complex in construction and assembly, and which is positive in operation and durable in use.

Other and further objects and advantages of the invention will become more evident from a consideration of the following specification when read in conjunction with the annexed drawings, in which:

Figure 1 is a front elevational view of a fine collecting and receipting device constructed in accordance with this invention, parts thereof being broken away to illustrate the constructional details.

Figure 2 is an end elevational view of the device illustrated in Figure 1.

Figure 3 is a side elevational view of a modification of the invention illustrated in Figures 1 and 2.

Figure 4 is a front elevational view of the fine collecting and receipting device constructed in accordance with the modification, parts thereof having been removed and other parts thereof being broken away to illustrate the constructional details of the machine.

Figure 5 is a vertical cross-sectional view of the device taken on the horizontal plane of line 5—5 of Figure 7, looking in the direction of the arrows, the component elements of the device being shown in their respective inoperative positions.

Figure 6 is a vertical cross-sectional view of the device shown in Figure 5, the component elements thereof being illustrated in their operative positions.

Figure 7 is a horizontal cross-sectional view of the device illustrated in Figures 5 and 6.

Figure 8 is an enlarged detail cross-sectional view taken on the horizontal plane of line 8—8 of Figure 3, looking in the direction of the arrows.

Figure 9 is a front elevational view of the removable ticket stub stacking element.

Figure 10 is an enlarged perspective view illustrating the construction of the carriage element.

Figure 11 is a side elevation of a ticket after having been receipted by the machine, the severed stub being shown in dotted outline.

Referring now more specifically to the drawings, reference numeral 20 designates, in general, a coin collecting and receipting device constructed in accordance with the present invention. As illustrated therein, the device 20 is seen to comprise a vertically elongated substantially hollow rectangular casing including a pair of vertically

extending side walls 22, 24 integrally connected adjacent their respective upper ends by a top wall 26. The lower ends of the side walls 22, 24 are outwardly flared at 28, 30, respectively, and are integrally formed with an enlarged substantially rectangular bottom wall 32.

A substantially horizontally extending shaft 34 is journaled for rotation in spaced aligned openings 36, 38 formed in the side walls 22, 24, respectively, and its ends project beyond the remotely positioned side surfaces thereof. One of the projecting ends of the shaft 34 receives therein a hub 40 of a crank arm 42 having a knob 44 rotatably mounted thereon by a bolt 46. The hub 40 is fixedly secured to the shaft 34 for rotation therewith by means of the set screw 48.

The other projecting end of the shaft 34 has fixedly secured thereon for rotation therewith a cam generally indicated by reference numeral 50. The cam is seen to comprise a pair of cam discs 52, 54 held in spaced, substantially parallel relation by means of a plurality of spaced cylindrical pins 56 which are fixedly secured thereto. A collar 58 is inserted into aligned off-center openings formed in the discs 52, 54 and the latter is then press fitted over the other projecting end of the shaft 34 whereby the collar and discs rotate therewith.

The pins 56 serve as ratchets for a pawl 60 forming one arm of a bell crank lever 62 pivotally mounted on the side wall 22 by the screw 64. The other arm 66 is connected with one end of a helicoidal spring 68 which has its other end anchored on a pin 70 which projects laterally from the upper end of the side wall 22. The counter-clockwise movement of the bell crank lever 62 is limited by a stop pin 72 disposed in the path of rotation of the arm 66.

The cam discs 52, 54 are provided with shoulders 74, 76, respectively, to which further reference will be made, and the disc 52 has fixedly secured thereon a laterally projecting crank pin 78 adjacent the circumference thereof.

One end of a link 80 is locked on the crank pin 78 by a bearing collar 82 while the other end thereof is offset at 84 and has fixedly secured thereto one end of a laterally offset pin 86. The projecting end of the pin 86 receives one end of a helicoidal spring 88 which has its other end mounted on a pin 90 which projects laterally from the flared lower end portion 28 of the side wall 22.

A cylindrical sleeve 92 is secured to the shaft 34 for rotation therewith between the side walls 22, 24. The opposite ends of the sleeve 92 terminate in cam members 94, 96 positioned adjacent the confronting sides of the side walls 22, 24, respectively, and the opposite ends of a rod 98 are fixedly secured to the cams 94, 96 and extends therebetween with the longitudinal axis thereof being positioned substantially parallel to the longitudinal axis of the shaft 34.

A substantially cylindrical rod 100 extends between the side walls 22, 24 and its ends are supported therein above the shaft 34. A substantially rectangular block 102 having a longitudinally extending offset bore 104 is mounted for rotation on the rod 100, and one end of an elongated substantially rectangular plate 106 is affixed thereto and depends therefrom by counter-sunk bolts 108. The lower end of the plate 106 is constructed with a plurality of openings which receive therethrough the necked down threaded ends of a plurality of coin sensing pins 110, 112 and 114. The pins 110, 112 and 114 are secured on the plate 106 by nuts 118, and are of different axial dimensions. Of these pins, pin 110 has the smallest axial dimension, pin 114 is somewhat longer, and pin 112 has the longest axial dimension.

A substantially rectangular face plate 120 is fixedly secured to the side walls 22, 24 by bolts 122 and is provided with a plurality of spaced apertures 124, 126 and 128 which are adapted to register with the pins 110, 112 and 114. A substantially rectangular cover plate 130 extends across the upper end of the face plate 120 and is held in spaced relation relative thereto by a plurality

of spacer plates 132, 134, 136 and 138 which, when taken together, comprise a guide slot for a coin of large denomination, and the additional spacer plates 140 and 142 which coact with the spacers 132 and 138 to define a coin slot for a coin of lesser value. The face plate, cover plate and spacer are secured together by rivets 144.

An elongated substantially rectangular block 146 is fixedly secured to the cover plate 130 by screws 148 and has a horizontal bore 150 formed therein adjacent the lower end thereof. A substantially U-shaped member 152 having a pair of spaced substantially parallel arms 154, 156 apertured at 158 and 160, respectively, and a bight 162 is pivotally mounted on the opposite ends of a rod 164 which extends through the apertures 158, 160 and the bore 150.

An elongated substantially rectangular plate 165 has its upper end, together with a horizontally elongated rectangular strip or member 166, fixedly secured to the bight 162 by screws 168. The member 166 has a laterally and inwardly extending portion 170 which extends through a notch 172 formed in the edge of the cover plate 120 intermediate its ends and into a recess 174 formed in the adjacent edge of the side wall 22. The portion 170 terminates in an outwardly projecting tongue 176 disposed in the path of movement of the shoulders 74, 76.

The lower end of the plate 165 is provided with a plurality of apertures 177 which normally are aligned with the apertures 124, 126 and 128.

A leaf spring 178 has one of its ends engaging against the bight 162 while the other end thereof is fixedly secured to the block 146 by screws 179 whereby the plate 165 is constantly biased for pivotal movement in a counter-clockwise direction, and the rod 164 mounted in the block 146 is held against axial displacement from the bore 150 by means of the set screw 180 and end clips 182.

A pair of substantially rectangular plates 184, 186 are mounted on the side wall 22 by bolts 188 and are held in spaced relation relative to each other by upper and lower horizontally elongated spacer plates 190 and 192, respectively, to form a ticket receiving channel 194 therebetween.

A vertically elongated, substantially rectangular block 196 is mounted against the outer face of the plate 186, and the plates 184, 186, 190, 192 together with the block 196 are secured to the side wall 24 by means of the bolts 198.

As is seen in Figures 5, 6 and 7, the plates 184, 186 are provided with a plurality of guide passages 200, 202 so arranged as to spell out the word "Paid." The guide passages 200, 202 are adapted to receive for reciprocation therethrough a plurality of elongated cylindrical punches 204 having enlarged heads 206 counter-sunk in a substantially rectangular mounting plate 208. A backing plate 210 engages against the mounting plate 208 to prevent the axial displacement of the punches 204, and the plates 208, 210 are secured together by the reduced threaded ends 212 of a pair of cylindrical, vertically spaced elongated smooth surfaced guide bolts 214 which are mounted for reciprocation in roller bearings 216 held against axial displacement by clip rings 218.

Referring now to Figures 5, 6 and 10, a carriage 220 is provided and is seen to comprise a horizontal substantially rectangular central body portion 222 from which arises a substantially rectangular flange 224 having a pair of laterally spaced openings 226 formed therein, and a pair of depending cam follower arms 228, 230 depending from each side thereof.

As is seen in the drawings, the flange 224 is secured to the upper ends of the plates 208, 210 by bolts 232 which pass therethrough and through the openings 226 and are locked against displacement by the nuts 234. The central body portion 222 extends transversely of the sleeve 92 and the cam follower arms 228, 230 are positioned in sliding contact with the cams 94 and 96,

respectively, and the cams 94 and 96 are also in engagement with opposite sides of the backing plate 210.

A substantially rectangular flange 236 is secured to the lower ends of the mounting and back plates 208 and 210, respectively, by the bolts 238 and nuts 240, and terminates at its upper end in a lip 239 directed inwardly toward the sleeve 92 for engagement therewith between the cams 94, 96 to prevent axial shifting of the shaft 34 relative to the side walls 22, 24.

The lower end of the plate 184 has fixedly secured thereto a depending pin 242 to which one end of a helicoidal spring 244 is anchored. The other end of the spring is looped at 246 and is secured in an opening 248 formed in the lower end of the plate 106 whereby the plate is constantly biased for movement toward the sleeve 92.

Referring now more specifically to Figures 7 and 8, it is seen that the side wall 24 is provided with a recess 250 to receive an extension 252 of the mounting plate 208 which terminates externally of the side 24 in a vertically extending cross-plate 254. A substantially L-shaped member having a flange 256 integrally formed with a knife blade 258 is fixedly secured to the cross-plate 254 by bolts 260 and nuts 262. As is seen in the dotted line construction in Figure 1, the flange 256 is recessed at 264 and receives therethrough a substantially rectangular block 266 which is also secured to the cross-plate 254 by a bolt 268. The block 266 is provided with a bore 270 which confronts a tine 272 mounted on a substantially rectangular plate 274 having enlarged circular openings 276 adjacent a side thereof. The openings 276 communicate with vertically extending slots 278 for detachable connection with a pair of screws 280 threaded into the block 196. A fixed substantially rectangular plate 282 having a knife edge slot 284 aligned with the ticket guide passage 194 is fixedly secured to the block 196 by screws 286 and is slidably engaged by the knife blade 258.

Coin stop pins 288, 290, 292 and 294 are threaded into the plate 120 below the above described coin passages and are adapted to releasably support coins intermediate the openings 124, 126, 128 and 174 to serve a function to be described, and a coin receiving receptacle (not shown) is supported on the base wall 32 below the lower ends of the plates 120 and 165.

The device 20 is adapted to be enclosed within a suitable housing 295 with the crank lever 42 extending exteriorly therefrom, and the housing 295 is provided with a slot 296 formed in a side wall 298 thereof to permit the introduction of a ticket 300 into the ticket passage 194.

The ticket 300 is seen to comprise a substantially T-shaped sheet of stiff paper having a stem 302 on which is inscribed data identifying the offense committed and other necessary information to identify the offender. Corresponding data is placed on the stub 304 which is adapted to be severed from the stem along the dotted line 306.

The cross-head 308 is wider than the guide passage 194 and serves as stop means to prevent the insertion of the ticket into the passage 194 beyond a given point as well as to function as a handle for the ticket.

The pins 290 and 294 are angularly displaced a distance less than the diameter of a fifty cent piece, and the pins 288 and 290 are arranged at an angular inclination less than the diameter of a twenty-five cent piece. The pin 292 is set at a distance less than the diameter of a twenty-five cent piece with respect to the nearest point on a quarter resting on the pins 288 and 290.

In operation, let it be assumed that a violation has occurred and the necessary information has been entered on the ticket 300. The recipient of the ticket grasps the cross-head 308 and inserts the stem 302 and the stub 304 through the slot 296 and into the passage 194 until the handle strikes the side wall 298. At this time the stub has passed through the knife edged slot 284 and confronts

the knife blade 258. The stub 304 is now positioned between the bore 270 and the tine 272.

The operator then inserts a coin into either of the two above defined coin receiving passages, and should it be less than a quarter it will pass directly therethrough and will pass between the plates 120 and 165 for collection in the receptacle 167. The same will occur if a quarter is inserted into the fifty cent coin passage.

Now let it be assumed that a quarter 320 has been inserted into the coin passage defined by the spacer plates 132, 138, 140 and 142. The coin 320 will come to rest on the pins 288, 290. Rotation of the shaft will cause the shoulders 74, 76 to engage the underside of the tongue 176 but will not permit the pawl 60 to pass behind the ratchet pin 56.

As the shaft 34 was turned under these circumstances the cams 94, 96 and rod 98 were also rotated. However, since the cam 50 turned less than 90°, the cams 94 and 96 were not turned a sufficient amount to bring their respective high sides into engagement with the plate 210 to effect a punching of the ticket 300, and the rod 98 while engaging and pivoting the plate 106 clockwise did not move the latter a sufficient distance to displace the coin 320 from the pins 288, 290.

Release of the knob 44 at this point will effect a counter-clockwise movement of the cam 50 under the influence of the spring 88, and the parts assume the positions shown in Figure 5.

If a second quarter 322 be inserted it will come to rest tangentially against the quarter 320 and pin 292. Now if the shaft 34 is rotated, the pin 114 will engage thereagainst to displace it from the pin 292 and quarter 320 while at the same time the pin 110 displaces the quarter 320 from the pins 288, 290.

This displacement takes place as the plate 165 is pivoted clockwise and simultaneously moves the tongue 176 out of the path of the shoulders 74, 76 of the cam 50. As the shaft rotates beyond 90° the high side of the cam 50 engages against the tongue 176 to hold the plate 165 in its elevated position.

Simultaneously with this movement beyond 90°, the rod 98 passes out of engagement with the plate 106, and the latter, under the influence of the spring 234, is moved toward the sleeve 92 to effect disengagement of the pins 110, 114 from the coins. The coins now being released fall into the receptacle 167. The pin 78 having also passed beyond 90° rotates to effect a quick turning movement on the shaft 34, and but slight manual effort is required, after the pin 78 has passed its lowermost dead center position with respect to the pin 90, to return the handle and its associated elements to their original positions, as is illustrated in Figure 5.

After the coins have been released, the high side of the cam 50 passes the tongue 176 whereby the tension of the leaf spring 178 effects a pivotal movement of the plate 165 to move the plate to the position shown in Figure 5.

As the coin releasing operation takes place, the cams 94, 96 are rotated so that the high sides thereof engage the plate 210 and force the punches 204 to penetrate the ticket 300. As the same time the block 266 advances toward the tine 272 and impales thereon the stub 304 as the knife blade 258 advances thereto and severs the stub 304 from the ticket 300.

The high sides of the cams next engage the depending cam follower arms 228, 230 of the carriage causing the plates 208, 210 to move in the opposite direction to release the ticket 300 from the punches 204.

Movement of the plates 208, 210 in this opposite direction results in the return of the knife blade 258 and the block 266 to their respective original positions with the stub 304 firmly held on the tine 272 behind the enlarged head 273 thereof.

The operator now removes the remaining portion of

the ticket from the device and the machine is ready for another cycle of operation.

At periodic intervals, an authorized agent collects the coins and removes the plate 274 together with the impaled stubs from the block 196 and replaces it with another.

In the modification shown in Figures 3 and 4, the device 20 is identical in all respects to the above described embodiment with the exception of the stub severing means, and consequently, elements of the modification finding their counter-parts bear like reference numerals.

In this modification, a flat elongated substantially rectangular knife blade 400 having a knife edge 402 has one of its ends pivotally mounted on a bolt 404 above the knife slot 284. The other end thereof is angularly inclined away from the slot 284 towards the cross-plate 254. The cross-plate 254 has mounted thereon by the bolt 408 and nut 410, one side 406 of an L-shaped angle member 412. The other side 414 of the angle member 412 extends toward the blade 400 and is provided with a vertical elongated slot 416 in which is slidably received a screw 418 threaded into the lower end of the blade 400.

Thus as the cross-plate 254 is actuated, the blade 400 swings across the knife slot 284 and severs the stub 304 which is impinged on the tine 272, as before.

Having described and illustrated two embodiments of this invention in detail, it will be understood that they are offered merely by way of example, and that the invention is to be limited only by the scope of the appended claims.

What we claimed is:

1. A coin operated ticket receiving device for a ticket having a stub portion, said device comprising a substantially hollow rectangular housing having a pair of opposed open ends, a coin receiving member mounted on said housing and extending across an end thereof, a plurality of coin sensing elements mounted in said housing for relative movement toward and away from said coin receiving member, a ticket receiving casing having a ticket guide passage therethrough, means fixedly securing said ticket receiving casing on said housing, said ticket receiving casing extending across the open side of said housing, said ticket receiving casing having a plurality of spaced aligned apertures extending transversely therethrough on each side of said passage, a mounting plate, said mounting plate having a plurality of spaced elongated punches loosely mounted thereon and projecting laterally therefrom, a backing plate for said mounting plate, said backing plate being adapted to extend across one of the respective ends of said punches to prevent displacement thereof from said mounting plate, means mounting said mounting and backing plate for reciprocation on said ticket receiving casing with said punches slidably engaging within said aligned apertures, cam means mounted in said housing, said cam means being rotatable to effect reciprocation of said backing and mounting plates and to effect actuation of said coin sensing elements, a knife blade mounted on said housing, said knife blade being disposed substantially adjacent said guide passage, a second knife blade fixedly secured to said mounting plate for reciprocal movement toward and away from said first knife blade to effect a shearing action of said stub from said ticket, and means operable to prevent movement of said punches if said sensing elements fail to encounter coins in said coin receiving member.

2. A coin operated ticket receiving device for a ticket having a stub comprising an elongated substantially hollow rectangular housing having a pair of opposed open ends and a pair of spaced substantially parallel side walls, a top wall integrally connected the upper ends of said side walls, a bottom wall integrally connecting the lower ends of said side walls, a face plate fixedly secured to said housing and extending across one of said open ends thereof, a cover plate fixedly secured to said face plate in spaced relation relative thereto, coin guide means disposed

between said face and cover plate, a coin retaining plate pivotally mounted on said cover plate and extending over a portion of said face plate, said coin retaining plate and said face plate having a plurality of spaced aligned apertures extending transversely therethrough, a plurality of coin supporting pins fixedly secured to said face plate and normally holding said coin retaining plate relatively spaced therefrom, means normally biasing said coin retaining plate for pivotal movement towards said face plate, an elongated substantially rectangular strip of material fixedly connected to said coin retaining plate and projecting laterally beyond one of said side walls, a shaft mounted and supported for rotation in said side walls and having end projections therebeyond, a cam mounted on the shaft projection adjacent said one side wall, said cam having a plurality of circumferentially spaced ratchet members mounted thereon and a radially extending shoulder, said strip having its said projection normally disposed in the path of movement of said shoulder, pawl means pivotally mounted on said one side wall, means constantly tending to urge said pawl into engagement with said ratchet members, means connected on said housing and fixed to said cam, said last named means first biasing said shaft against rotation in one direction and secondly adding its force to the turning movement of said shaft, a handle fixedly secured to the other projecting end of said shaft, a sleeve fixedly mounted for rotation on said shaft and disposed within said housing, said sleeve having a cam on each end thereof positioned adjacent said side walls, a pair of substantially rectangular plates, a spacer plate interposed between said pair of plates at a pair of opposed sides thereof to form a substantially rectangular ticket guide passage having opposed open ends, said spacer and pair of plates being fixedly secured to said housing and extending across the other open end thereof, said pair of plates having a plurality of spaced aligned transversely extending apertures formed therein on each side of said passage, a mounting plate having a plurality of punches loosely mounted thereon, a backing plate juxtaposed against said mounting plate to prevent displacement of said punches therefrom, means supporting said mounting plate, said backing plate and said punches for reciprocation on said pair of plates with said punches being slidably disposed in said apertures formed in said pair of plates, a carriage fixedly secured to said mounting and backing plates and having a pair of laterally offset arms, said arms and said backing plate engaging opposite sides of said cams formed with said sleeve to effect a reciprocation of said punches, a rod mounted on said housing with its axis substantially parallel to the axis of said shaft, a plate pivotally mounted on said rod, means constantly biasing the free end of said last named plate for movement towards said shaft, a plurality of pins mounted on said plate adapted for movement with said plate toward said face and coin retaining plates to sense coins retained therebetween, a rod mounted on and supported by said cams formed with said sleeve, said last named rod being adapted to engage said last named plate upon rotation of said shaft to effect movement of said last named plate towards said face and coin retaining plates, a knife blade fixedly secured to said pair of plates adjacent one end and side of said passage, a tine fixedly secured to said pair of plates adjacent said one end and said one side of said passage, a knife blade fixedly secured on said mounting plate adjacent the other side of said one end of said passage and confronting said first knife blade, a block having a bore fixedly secured to said mounting plate with said bore confronting said tine, and said shaft upon rotation effecting release of said coins and reciprocation of said punches across said passage to penetrate said ticket and to sever said stub thereof projecting from said one end of said passage to impale the same on said tine.

3. A coin operated ticket receiving device for a ticket having a stub comprising a housing having a pair of

opposed open ends, a face plate fixedly secured to said housing and extending across one of said open ends thereof, a cover plate fixedly secured to said face plate in spaced relation relative thereto, coin guide means disposed between said face and cover plates, a coin retaining plate pivotally mounted on said cover plate and extending over a portion of said face plate, said coin retaining plate and said face plate having a plurality of spaced aligned apertures extending transversely therethrough, a plurality of coin supporting pins fixedly secured to said face plate and normally holding said coin retaining plate relatively spaced therefrom, means normally biasing said coin retaining plate for pivotal movement towards said face plate, an elongated substantially rectangular strip of material fixedly connected to said coin retaining plate and projecting laterally beyond said housing, a shaft mounted for rotation in said housing and having projections extending beyond opposite sides thereof, a cam mounted on one of said shaft projections adjacent one side of said housing, said cam having a plurality of circumferentially spaced ratchet members mounted thereon and a radially extending shoulder, said strip having its said projection normally disposed in the path of movement of said shoulder, pawls means pivotally mounted on said housing, means constantly tending to urge said pawl into engagement with said ratchet members, means mounted on said housing and connected with said cam, said last named means first biasing said shaft against rotation in one direction and secondly adding its force to the turning movement of said shaft, a handle fixedly secured to the other projecting end of said shaft, a sleeve fixedly mounted for rotation on said shaft and disposed within said housing, said sleeve having a cam on each end thereof positioned adjacent said sides of said housing, a pair of substantially rectangular plates, a spacer plate interposed between said pair of rectangular plates adjacent a pair of opposed sides thereof to form a substantially rectangular ticket guide passage having opposed open ends, said spacer plate and pair of rectangular plates being fixedly secured to said housing and extending across the other open end thereof, said pair of rectangular plates having a plurality of spaced aligned transversely extending apertures formed therein on each side of said passage, a mounting plate having a plurality of punches loosely mounted thereon, a backing

plate juxtaposed against said mounting plate to prevent displacement of said punches therefrom, means supporting said mounting plate, said backing plate and punches for reciprocation on said pair of rectangular plates with said punches being slidably disposed in said apertures formed in said pair of rectangular plates, a carriage fixedly secured to said mounting and backing plates and having a pair of laterally offset arms, said arms and said backing plate engaging opposite sides of said cams formed with said sleeve to effect a reciprocation of said punches, a rod mounted on said housing with its axis substantially parallel to the axis of said shaft, a plate pivotally mounted on said rod, means constantly biasing the free end of said last named plate for movement toward said shaft, a plurality of coin sensing pins mounted on said last named plate and adapted for movement towards said face and coin retaining plates to sense coins retained therebetween, a rod mounted on and supported by said cams formed with said sleeve, said last named rod being adapted to engage said last named plate upon rotation of said shaft to effect movement of said last named plate towards said face and coin retaining plates, a knife blade fixedly secured to said pair of rectangular plates adjacent one end and side of said passage, a tine fixedly secured to said pair of rectangular plates adjacent said one end of said passage, a knife blade mounted on said mounting plate adjacent the other side of said one end of said passage and confronting said first knife blade, a block having a bore fixedly secured to said mounting plate with said bore confronting said tine, and said shaft upon rotation effecting release of said coins and reciprocation of said punches across said passage to penetrate said ticket and to sever said stub thereof projecting from said one end of said passage to impale the same on said tine.
